UNITED STATES PATENT OFFICE.

THOMAS M. CATE, OF NORFOLK, VIRGINIA.

RAIL JOINT AND RAIL.

Application filed November 10, 1925. Serial No. 68,182.

To all whom it may concern:

Be it known that I, THOMAS M. CATE, a citizen of the United States, residing at Norfolk, in the county of Norfolk and State of Virginia, have invented a new and useful Rail Joint and Rail, of which the following is a specification.

This invention aims to provide novel means for joining the ends of two railroad rails in such a way that separation of the rail ends, either longitudinally or transversely, will be avoided, low joints being obviated, material being saved, track work being cut down, and safety being promoted.

It is within the province of the disclosure to improve generally and to enhance the utility of devices of that sort to which the invention appertains.

Although a preferred form has been delineated, it will be understood that a mechanic, working within the scope of what is claimed, may make changes and alterations without departing from the spirit of the invention.

In the drawings:—Figure 1 shows in top plan, a device constructed in accordance with the invention; Figure 2 is a side elevation; Figure 3 is a cross section on the line 3—3 of Figure 2; Figure 4 is a section on the line 4—4 of Figure 2.

In the drawings, there is shown a pair of rails comprising balls 1, webs 2, and flanges 3, the balls, the webs and the flanges of both rails being cut away at opposite sides of the rails to form shoulders 4 which are inclined longitudinally of the rails, to form an inclined end surface 5 in each rail, cooperating with the shoulder 4 of the other rail, and to form overlapped longitudinal extensions 6 in the rails, those portions 7 of the webs 2 which are located in extensions 6 being provided upon their inner surfaces with complementary recesses 8, the webs 2 having seats 9 located outwardly of the shoulders 4 and beyond the ends of the recesses 8. The joint includes a member comprising a base 10 cooperating with the flanges 3 of the rails, and an upstanding wing 11 received in the recesses 8 and in the seats 9, securing elements 12 and 14, such as bolts, connecting the webs 2 and the wing 11, certain of the securing elements, to wit, the securing elements 14, being located outwardly of the shoulders 4, and beyond the ends of the recesses 8.

The device above described avoids the use of fish plates or angle bars, and presents a construction in which the rail ends cannot separate, either longitudinally or transversely, low joints and a battering of the rail ends being reduced to a minimum.

Having thus described the invention, what is claimed is:—

1. A pair of rails comprising balls, webs, and flanges, the balls, the webs and the flanges of both rails being cut away at opposite sides of the rails to form shoulders which are inclined longitudinally of the rails, to form an inclined end surface in each rail, cooperating with the shoulder of the other rail, and to form overlapped longitudinal extensions in the rails, those portions of the webs which are located in the extensions being provided upon their inner surfaces with complementary recesses, and the webs having seats located outwardly of the shoulders and beyond the ends of the recesses; a member comprising a base cooperating with the flanges of the rails, and an upstanding wing received in the recesses and in the seats; and securing elements connecting the webs and the wing, certain of the securing elements being located outwardly of the shoulders, and beyond the ends of the recesses.

2. A pair of rails comprising balls, webs, and flanges, the balls, the webs and the flanges of both rails being cut away at opposite sides of the rails to form shoulders which are inclined longitudinally of the rails, to form an inclined end surface in each rail, cooperating with the shoulder of the other rail, and to form overlapped longitudinal extensions in the rails, those portions of the webs which are located in the extensions being provided upon their inner surfaces with complementary recesses, and the webs having seats located outwardly of the shoulders and beyond the ends of the recesses; a member comprising a base cooperating with the flanges of the rails, and an upstanding wing received in the recesses and in the seats; and securing elements connecting the webs and the wing.

3. A pair of rails comprising balls, webs, and flanges, the balls, the webs and the flanges of both rails being cut away at opposite sides of the rails to form shoulders which are inclined longitudinally of the rails, to form an inclined end surface in

each rail, cooperating with the shoulder of the other rail, and to form overlapped longitudinal extensions in the rails, those portions of the webs which are located in the extensions being provided upon their inner surfaces with complementary recesses; a member comprising a base cooperating with the

flanges of the rails, and an upstanding wing received in the recesses; and a securing element connecting the webs and the wing. 10

In testimony that I claim the foregoing as my own, I have hereto affixed my signature.

THOMAS M. X CATE.
